UNITED STATES PATENT OFFICE.

GEORGE W. McFARLAND, OF BRANDYWINE SUMMIT, PENNSYLVANIA.

CLAY-PRESS ATTACHMENT.

SPECIFICATION forming part of Letters Patent No. 245,649, dated August 16, 1881.

Application filed February 9, 1881. (No model.)

To all whom it may concern:

Be it known that I, GEORGE W. McFARLAND, of Brandywine Summit, Delaware county, Pennsylvania, have invented Improvements 5 in Clay-Press Attachments, of which the following is the specification.

My invention relates to that class of apparatus employed for the purpose of removing the surplus water from the slip in preparing 10 clay for the manufacture of earthenware articles.

The object of my invention is to facilitate the manipulation of the parts of the apparatus, as well as reduce the expense of making the 15 latter.

In the drawings, Figure 1 is an elevation, in part section, of a clay-press illustrating my improvements, and Fig. 2 is an enlarged view of 20 part of the apparatus; Fig. 3, a perspective view, showing a modification.

What is technically called the "press" consists of a series of boards, A, separated to 25 leave intervening spaces to receive the bags B, each of the latter consisting of a sheet of canvas doubled and folded at the edges.

Heretofore it has been customary to provide each bag with a metal nozzle connected thereto, and also fastened to a flange at the upper edge of one of the boards A, the slip or clay 30 solution being fed to said nozzle through a stationary pipe extending over the press. This construction results in the consumption of considerable time in placing the bags in and removing them from the press. The whole 35 arrangement is clumsy, and it is difficult to manipulate the bags, whether filled or empty.

I make the press of any suitable number of boards A in the ordinary manner; but in place of fastening the nozzles C to the leaf I make 40 each nozzle with two flanges, b b', sufficiently separated to receive between them the parting-pieces a a, as shown in Figs. 1 and 2 of the accompanying drawings. The end of each nozzle below the flange b' is threaded and provided with a nut, d, between which and the flange b' the bag is clamped, as shown. The 45 upper end of the nozzle is flaring, and adapted to receive the conical end of a tubular branch, D, projecting from the horizontal pipe E, into which the slip is forced by a pump, as usual. Each branch is provided with a cock, f, which 50 may be turned so as to permit or cut off the flow through the pipe.

A rubber ring, g, may be carried in the mouth of the nozzle C, or around the end of 55 the branch D, so as to aid in closing the joint between the branch and the nozzle.

By the above construction the operations of the press are greatly facilitated, for the pipe E and its branches are permanently fixed, requiring no manipulation, while each nozzle may by a single movement be tightly connected to or removed from its branch, and each nozzle, with its bag, may be inserted between the leaves of the press or withdrawn, 60 thus affording an opportunity of washing the bag or removing the contents.

Owing to the fact that the pipe E and its branches are stationary the apparatus costs much less than when the pipe and branches 65 are composed of separate pieces, as heretofore.

In order to compensate for the shrinkage of the press the pipe E may be divided, threaded at the ends with threads running in opposite directions, and provided with a screw-coupling 70 piece, J, the turning of which will effect a longitudinal adjustment of the nozzles requisite to bring the latter in proper position. In place of this each branch may be an L-shaped elbow capable of swinging to a slight extent, 75 as shown in Fig. 3.

I claim—

1. The combination, in a clay-press, of a stationary main pipe, E, provided with fixed or 80 movable branches D, and bags B, provided with metal sockets having flaring mouths 85 adapted to receive the ends of the branches, substantially as set forth.

2. The combination, with the pipe E and its branches, arranged above a clay-press, of 90 an adjusting device, J, for the purpose set forth.

3. The combination, with the bag B of a clay-press, of a nozzle, C, having a flange, b', and nut d, for clamping the bag against said 95 flange, and provided with a mouth adapted to receive the end of the branch D, and with a packing, g, substantially as set forth.

In testimony whereof I have signed my name to this specification in the presence of two subscribing witnesses.

GEORGE W. McFARLAND.
